United States Patent Office

Des. 219,389
Patented Dec. 8, 1970

219,389

TEACHING DOLL

Sallie Ann Coltharp, 9128 E. 49th St.,
Tulsa, Okla. 74145

Filed Nov. 14, 1969, Ser. No. 20,092

Term of patent 7 years

Int. Cl. D21—02

U.S. Cl. D34—4

Fig. 1.

Fig. 2.

Fig. 3.

FIG. 1 is a front view of the teaching doll showing my new design.

FIG. 2 is a side view of FIG. 1.

FIG. 3 is a front view showing a variation of the doll face with the eye lids in a closed position.

I claim:

The ornamental design for a teaching doll, as shown and described.
